CLAIM

The ornamental design for a card holder, as shown and described.

DESCRIPTION

FIG. 1 is a front perspective view of a card holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view showing the card holder in an expanded state; and,

FIG. 10 is a rear view showing the card holder in an expanded state.

The broken lines in the drawings illustrate the portions of the card holder, which form no part of the claimed design.

1 Claim, 10 Drawing Sheets
